UNITED STATES PATENT OFFICE

158,464

PORTABLE DISPLAY STAND OR SIMILAR
ARTICLE

Philip Hopp, New York, N. Y., assignor to The
Hopp Press Inc., New York, N. Y., a corporation
of New York

Application January 21, 1950, Serial No. 7,377

Term of patent 14 years

(Cl. D80—9)

To all whom it may concern:

Be it known that I, Philip Hopp, a citizen of the United States, residing at New York, in the county of New York and State of New York, have invented a new, original, and ornamental Design for a Portable Display Stand or Similar Article, of which the following is a specification, reference being had to the accompanying drawings, forming part thereof.

The figure is a perspective view of a portable display stand or similar article showing my new design.

The side of the portable display stand or similar article opposite the side shown is similar in appearance.

I claim:

The ornamental design for a portable display stand or similar article, as shown and described.
PHILIP HOPP.
